Moore & Blum
ATTORNEY

UNITED STATES PATENT OFFICE.

FREDERICK H. GOLDHARDT, OF WEEHAWKEN, NEW JERSEY.

LOCKING DEVICE.

Application filed March 8, 1928. Serial No. 260,014.

My invention relates to a new and improved lock hook for garments.

However, it is to be understood that the locking device or mechanism disclosed herein can be generally used for a great many other purposes in addition to locking garments on hooks.

One of the objects of my invention is to provide a new and improved lock hook where-
10 by a coat or other garment can be securely locked into position upon a suitable supporting hook.

Another object of my invention is to provide a device of this character which shall be
15 simple, cheap to construct, and which will have a minimum number of moving parts.

Another object of my invention is to provide a device in which the weight of the garment on the hook will automatically lower
20 it to its "free" position when the lock is open.

Other objects of my invention will be set forth in the following description and drawings which illustrate a preferred embodiment thereof, it being understood that the above
25 general statement of the objects of my invention is intended to generally explain the same and not to limit it in any manner.

Fig. 1 is a perspective view showing the improved device.

30 Fig. 2 is a sectional view on the line 2—2 of Fig. 3.

Fig. 3 is a sectional view on the line 3—3 of Fig. 2.

Fig. 4 is a side elevation of the coat hook.

35 Fig. 5 is a perspective view of the hat hook.

The device comprises the U-shaped casing 1 having lateral flanges 2, which can be suitably connected to any suitable support S. The coat hook 3 is provided with an upstanding portion 4 which is provided with a ratchet 5 whose teeth are downwardly inclined. The upstanding hook portion 4 is adapted to slide within the housing 1, being restrained from lateral movement by means of pins 6.

40 A lock L of any ordinary type is suitably connected to the side of the housing 1, as for example, by means of rivets 7. The lock L is provided with a key actuated ratchet 8 which is clearly shown in Fig. 3. By manipulating the lock L by means of a suitable key, the lock ratchet 8 can be caused to protrude within the housing 1 so as to engage the ratchet 5 and to restrain the hook 3 from any downward movement. The housing 1 is
50 provided with lugs 9 which are perforated

to serve as a mount for a pivot pin 10. The pivot pin 10 is suitably secured to the housing 1 and it serves as a support for the hat hook 11. The hat hook 11 is provided with an arm 12 which extends within the housing 1. The member 4 is provided with a longitudinal recess 14 in which the arm 12 is adapted to project so as to limit the sliding movement of the member 4 within the housing 1.

As shown in Fig. 1, the front of the housing 65 1 is cut away to leave an open space above and below the lugs 9. This limits the turning movement of arm 12, when the hook 3 is moved downwardly.

It will be noted that the coat hook 3 is provided with a wide lateral end 3' so that the ordinary hanger of a coat cannot be slipped over the hook.

The pivot pin 10 projects through an opening 10' in the coat hook 11. The ratchet 5 is 70 provided with a smooth head 15, and said ratchet 5 is held in place by means of a screw 5'.

The operation of the device is as follows:

The locked position of the parts is illus- 80 trated in Fig. 1. When it is desired to hang a coat upon the hook 3, the lock is operated by means of a suitable key so as to release the ratchet 8 from the ratchet 5. The hook 3 can now be moved downwardly and its weight 85 will tend to make it fall to its lower position. The downward movement of the coat hook 3 will cause the hat hook 11 to turn upwardly. The key can now be manipulated so as to urge the ratchet 8 into its operative position, and 90 the coat can now be placed upon the hook 3. The hook 3 can now be pushed upwardly into the locking position because the ratchet 8 can yield inwardly to permit this movement. The ratchet 8 automatically locks the hook 3 in its 95 upper and locking position.

To remove the coat it is merely necessary to manipulate the lock so as to release the ratchet 8 from the ratchet 5. The weight of the coat then forces the hook 3 downwardly simultaneously swinging the hat hook 11 upwardly. When the key of the lock has been manipulated to move the ratchet 8 to its inoperative position, said key cannot be removed from the lock. Hence, after a person 100 has completed using the device and has removed his coat, it is not possible for him to inadvertently remove the key.

I have described a preferred embodiment 110 of my invention, but it is clear that numerous

changes and omissions could be made without departing from its spirit.

I claim:

- 5 1. A locking device comprising a casing, a lower member slidably mounted in said casing, a movable latch device connected to said casing, connecting means intermediate said lower member and said latch device adapted to cause the outer operative end of said latch device to move away from said lower member, when said lower member moves downwardly, and means for locking said lower member in position.
- 10 2. A locking device comprising a casing having an opening in a wall thereof, a lower member having a slidable extension extending into said casing, a latch device superposed with respect to said lower member, said latch device being pivotally mounted on said casing, and having an extension fitting within a recess of the first-mentioned extension so that the upward movement of said lower member causes said latch device to be turned down-

wardly, and means for locking said lower member in position.

25

3. A locking device comprising a casing having a front wall provided with an opening, a lower member projecting in front of said front wall, said lower member having a slidable extension extending into said casing, the side walls of said casing having lugs adjacent said opening, a latch device pivotally mounted on said lugs and having an extension projecting into said casing and into a recess of the first-mentioned extension so that an upward movement of said lower member causes a downward turning of said latch device, one of the lateral faces of said slidable extension having ratchet teeth, and a lock controlled plunger associated with one of the side walls of the casing and projecting into said casing and adapted to engage said ratchet teeth.

30 35 40 In testimony whereof I affix my signature.

FREDERICK H. GOLDHARDT.
